DISPLAY BOX

Marjorie E. Jaques, Chicago, Ill., assignor to Wm. Wrigley Jr. Company, Chicago, Ill., a corporation of Delaware

Application January 18, 1937, Serial No. 121,066

1 Claim. (Cl. 206—44)

This invention relates to an improvement in display boxes and consists of the matters hereinafter described and more particularly pointed out in the appended claim.

5 The display box is of that general type which has a rearwardly inclined bottom and back walls, a front wall cut away to display the bulk of the goods contained in the box and an easel attachment to support the box in its inclined position.

10 The object of the present invention is to provide a construction of box of the kind with an easel attachment which is foldable against the back wall for insertion into the familiar slip-cover for shipment, and which is automatically brought to supporting position away from the box back by the weight of the goods in the box, when and as the box is set down to rest on its inclined bottom wall.

15 The box is made preferably from a single blank of cardboard or heavy paper, which may be shipped flat to the packer, by whom it is easily set up in box form.

20 The advantages of the invention will appear more fully as I proceed with my specification.

25 In the drawings:

Figure 1 is a plan view of a blank cut and scored to form the improved box.

Figure 2 is a perspective view of the box set up in display position, with its easel expanded to supporting position.

30 Figure 3 is a vertical section through Figure 2 in a plane indicated by the line 3—3 of Figure 2.

35 Figures 4, 5 and 6 are perspective views illustrating successive steps in folding the blank of Figure 1 to set up the box.

40 Figure 7 is a side elevation of the box showing it at the left when first placing it on a counter or other display platform, and at the right as it appears when by reason of the weight of the contents the easel is caused to expand to supporting position.

45 Referring now to that embodiment of the invention illustrated in the drawings:—10 indicates the blank as a whole. It comprises an elongated strip scored transversely to provide a back wall 11 of the box; a supporting member 12 and a base member 13 for the easel; and a bottom wall 14 and a front wall 15 for the box,—said parts being defined, respectively, by the transverse score lines 11^a, 12^a, 13^a and 14^a. The back wall 11 is longer than the supporting member 12 of the easel. The base member 13 of the easel is divided by a transverse score line 13^b into a wide section 13^c adjacent the supporting

member 12 of the easel and a narrower section 13^d adjacent the bottom wall 14.

5 The front wall 15 is cut away to provide a short upstanding wall part 15^a adjacent the bottom 5 14 and extending the width of the box, and narrow upright marginal front wall parts 15^b which project considerably beyond the edge of the wall part 15^a.

The blank includes side members 17, 17 which project laterally from the main length of the 10 blank and extend beyond the marginal front wall parts 15^b. They are defined therefrom by score lines 17^a, 17^a, which begin at the ends of the score line 14^a and extend in alignment with the lateral edges of the main part of the blank. The 15 side members 17, 17 extend at their upper ends to score lines 18, 18, which begin at the ends of the score line 14^a and are inclined at like angles to the score line 17^a. These angles determine the inclination that the bottom wall is to have to the vertical when the box is set up and resting on said bottom wall. 17^b, 17^b indicate the end walls of the box. 17^c, 17^c indicate glue flaps projecting laterally from said end walls and defined therefrom by score lines 17^d, 17^d. 20

25 Beyond the score lines 18, 18 are provided locking members 19, 19. The side edges of said locking members are cut at right angles to the score line 18. The sides next to the main blank are notched near their free ends to provide 30 locking tongues 19^a, 19^a. Score lines 19^b, 19^b, running parallel to the sides of the locking member, are provided to permit said tongues 19^a to fold upon the locking member. The opposite sides of the locking members are cut to provide laterally projecting locking tongues 19^c, 19^c in alignment with the tongues 19^a and which are adapted to fold upon score lines 19^d, 19^d. 35

40 In the main blank, near its lateral margins, are formed slits 20, 20 located in the score line 13^a, which defines the rear edge of the bottom wall 14. It is also provided with like slits 21, 21 spaced from the first named slits a distance equal to the distance between the score lines 19^b, 19^d of the tongues 19^a, 19^c of each locking member 19. The two pairs of slits are designed to receive the said locking tongues of the locking members 19,—the slits 20 to receive the tongues 19^a, 19^c, and the slits 21, 21 to receive the tongues 19^b, 19^d. 45

50 The improved box is set up as follows:

55 The wing members are first folded as shown in Figure 4, to break them along the score lines 17^a, 17^d, 18, 19^b and 19^d. Said wing members are then each in succession folded upon the score line 55

17^a to bring the score line 18 adjacent to the edge of the bottom wall 14. The associated locking member 19 is then swung upon said score line 18 below the bottom member 14, and the tongues 5 19^a and 19^c are in succession inserted respectively through the associated slots 20 and 21, as shown in Figure 5. The back wall 11 is then folded down upon the score line 11^a to bring its bottom edge down to the level of the rear edge of the 10 bottom wall 14 and against the rear faces of the upstanding tongues 19^c, 19^c, as shown in Figure 6. To permit this movement, the easel section 12 is folded upon the score line 12^a. The glue flaps 17^c, 17^c are then secured to the lateral margins of 15 the back wall 11. This will bring the box to the form shown in Figures 2 and 3 and completes the set-up of the box, which is ready for packing.

After the box has been packed and ready for shipment, the base member 13 of the easel is 20 folded upon itself along the score line 13^b to collapse the easel against the back of the box, as shown at the left in Figure 7. This leaves the two sections 13^c, 13^d of the base member 13 of the easel folded flat upon themselves and projecting 25 below the rear edge of the bottom wall of the box, as shown at the left in Figure 7.

When the box is to be placed on display, it is removed from the slip cover or other packaging means in which it is enclosed, and is set down 30 upon the table, counter or other support with the

depending, collapsed base member of the easel in engagement therewith. The weight of the contents of the box or a manual operation will then cause the easel member to expand, moving its supporting member 12 away from the back of the 5 box and unfolding the sections 13^c, 13^d of the base to swing them into flat position in the plane of the box bottom 14 as shown at the right in Figure 7.

While in describing my invention I have referred to a number of details of construction and arrangement of parts, it will be understood that the invention is not limited thereto except as is pointed out in the appended claim.

I claim as my invention:

A display box having a front wall, end walls, an upwardly and rearwardly inclined bottom wall, a rearwardly inclined back wall, and an easel member, said easel member comprising a supporting member connected to and foldable about the upper edge of said back wall, and a base member connected to and foldable about the bottom edge of said supporting member and the rear edge of said bottom wall, and said base member being foldable downwardly with reference to said bottom wall upon a transverse line between the bottom of said supporting member and the rear edge of said bottom wall to collapse said supporting member against said back wall.

MARJORIE E. JAQUES. 30
